(57) **CLAIM**

We claim the ornamental design for a gas grate, as shown
and described.

DESCRIPTION

FIG. 1 is a top perspective view of a gas grate of the present
disclosure;

FIG. 2 is a first side elevational view of the gas grate of FIG.
1;

FIG. 3 is a second side elevational view of the gas grate of
FIG. 1;

FIG. 4 is a third side elevational view of the gas grate of FIG.
1;

FIG. 5 is a fourth side elevational view of the gas grate of
FIG. 1;

FIG. 6 is a top plan view of the gas grate of FIG. 1;

FIG. 7 is a bottom plan view of the gas grate of FIG. 1;

FIG. 8 is a bottom perspective view of the gas grate of FIG.
1;

FIG. 9 is a top perspective view of a gas grate of the present
disclosure;

FIG. 10 is a first side elevational view of the gas grate of
FIG. 9;

FIG. 11 is a second side elevational view of the gas grate of
FIG. 9;

FIG. 12 is a third side elevational view of the gas grate of
FIG. 9;

FIG. 13 is a fourth side elevational view of the gas grate of
FIG. 9;

FIG. 14 is a top plan view of the gas grate of FIG. 9;

FIG. 15 is a bottom plan view of the gas grate of FIG. 9;

FIG. 16 is a bottom perspective view of the gas grate of FIG.
9;

FIG. 17 is a top perspective view of a gas grate of the present
disclosure;

FIG. 18 is a first side elevational view of the gas grate of
FIG. 17;

FIG. 19 is a second side elevational view of the gas grate of
FIG. 17;

FIG. 20 is a third side elevational view of the gas grate of
FIG. 17;

FIG. 21 is a fourth side elevational view of the gas grate of
FIG. 17;

FIG. 22 is a top plan view of the gas grate of FIG. 17;

FIG. 23 is a bottom plan view of the gas grate of FIG. 17;
and,

FIG. 24 is a bottom perspective view of the gas grate of FIG.
17.
